UNITED STATES PATENT OFFICE.

GARTH GRIFFITH GILPIN, OF RIVERSIDE, ILLINOIS, ASSIGNOR TO WALTER P. MURPHY, OF CHICAGO, ILLINOIS.

RELEASE-RIGGING BRACKET.

1,232,676.

Specification of Letters Patent. Patented July 10, 1917.

Original application filed December 17, 1915, Serial No. 67,403. Divided and this application filed July 14, 1916. Serial No. 109,244.

To all whom it may concern:

Be it known that I, GARTH GRIFFITH GILPIN, a citizen of the United States, residing at Riverside, in the county of Cook and State of Illinois, have invented certain new and useful Improvements in Release-Rigging Brackets, of which the following is a specification.

My invention relates to a release rigging, 10 that is, to an apparatus for manipulating the locking pin of a car coupler, and the object of the invention is to provide an improved bracket for supporting the operating rod of such apparatus.

15 In certain types of release riggings employing a revoluble crank rod for lifting the locking pin it is necessary, in order to disengage the release rigging from the coupler, when the coupler is to be repaired, for example, to remove the operating rod from the car.

20 My invention provides a bracket so constructed that it is possible to take the operating rod therefrom and replace the same 25 therein very quickly and conveniently without removing any part of the bracket from the car. The non-removability of the parts of the bracket is a desirable feature of the invention as there is always likelihood, 30 where bolts, cotter pins or other removable parts are used in a release rigging, that such parts will become lost or mislaid when the release rigging is removed from the car, or that they may be deliberately abstracted 35 from the bracket, thus incapacitating the release rigging by mischievous persons or by a repair man or some member of the train crew when such device or part is needed elsewhere. In its preferred form the bracket 40 of my invention is a unitary structure which is removable from the car only as a whole.

The invention is illustrated, in such preferred embodiment, in the accompanying drawing wherein—

45 Figure 1 is a fragmentary view, in perspective, of the end of a railway car and coupler showing a release rigging, comprising a bracket constructed in accordance with my invention applied to the car.

50 Fig. 2 is a perspective view of the bracket and part of the operating rod of the release rigging, and

Fig. 3 is a similar view showing the movable element of the bracket structure in po-

sition which it assumes when the rod is to be 55 removed from or replaced in the bracket.

Like characters of reference designate like parts in the several figures of the drawing.

Referring to the drawing, 10 designates the end sill of a railway car, 11 the dead 60 wood and 12 the coupler provided with a locking pin 13 having an eye 14.

The release rigging consists of an operating rod A, supporting devices B and C, and a link D connecting crank 15 of the 65 operating rod with the eye 14 of the locking pin. The operating rod is shown as formed with a handle 16.

The construction of supporting device B is shown particularly in Figs. 2 and 3. It 70 consists of a bracket 17 and removable closure device 18. The bracket is formed with an upper, outwardly projecting flange 19 and a lower, channel-shaped flange 20. The closure member 18, which is designed to 75 close the space between projections 19 and 20 of the bracket, is formed with a channel-shaped member 21 providing a bearing for operating rod A, this part of the closure element being formed to fit into the channel-shaped projection 20 on the bracket. The closure element terminates at its upper end in a preferably round stem 22 which passes through an opening 23 in projecting flange 19. After the parts of the bracket have 80 been assembled the upper end 24 of stem 22 is preferably bent over so that the closure element is permanently connected with the bracket.

The supporting device C may be the same 90 in its construction as supporting device B just described. Preferably, however, it is formed at its outer vertical edge with an outstanding projection 25 against which the end of the operating rod A bears so that the 95 rod is held in proper position on the car.

To remove the rod from the bracket it is lifted so as to free the closure devices which may then be raised until they are free from the channel-shaped flanges of the bracket 100 upon which they may be turned to the position shown in Fig. 3, permitting the operating rod to be removed from the brackets.

The link D has a slidable engagement with the crank 15 of the operating rod, being formed with an elongated loop 26 which extends over the rod and is held thereon by the retaining casting 27 which is secured to

the end of the rod. The link D terminates at its lower end in a spiral hook 28 which passes through the eye 14 of the locking pin. The invention herein claimed relating to the 5 bracket *per se* is not to be considered as limited to the details of construction of the operating rod and its connection with the locking pin which might be varied without affecting the function of the bracket. When 10 the operating rod has been removed from the car it may be turned so as to free hook 28 from the locking pin.

This application is a division of my co-pending application Serial No. 67,403, filed 15 December 17, 1915, in which the release rigging disclosed in both applications is claimed as an entirely. I do not claim in this application any of the novel features of the release rigging shown except the construction of the brackets or supporting devices for the operating rod.

I claim:

1. A device for supporting the operating rod of a coupler pin release rigging comprising a bracket adapted to be attached to a car and provided with projecting members one above the other, and a closure element for closing the opening between said projecting members which is slidably engaged with said upper projecting member and is provided with an inturned projecting part on which the rod bears in its operative position.

2. A device for supporting the operating rod of a coupler pin release rigging comprising a bracket adapted to be attached to a car and provided with projecting members one above the other, and a closure element for closing the opening between said 40 projecting members which is slidably engaged with said upper projecting member, the lower projecting member being formed at its outer edge with an upturned lip to provide a seat for said closure element when in operative position.

3. A device for supporting the operating rod of a coupler pin release rigging comprising a bracket adapted to be attached to a car and provided with projecting members 50 one above the other, and a closure element for closing the opening between said projecting members which is slidably engaged with said upper projecting member and is provided with an inturned projecting part on which the rod bears in its operative position, the lower projecting member being formed at its outer edge with an upturned lip.

4. A device for supporting the operating 60 rod of a coupler pin release rigging comprising a bracket adapted to be attached to a car and provided with projecting members one above the other, the upper of which is formed with a perforation, and a closure 65 element for closing the opening between said

projecting members having a stem passing slidably and revolvably through the perforation in the upper projecting member of the bracket.

5. A device for supporting the operating 70 rod of a coupler pin release rigging comprising a bracket adapted to be attached to a car and provided with projecting members one above the other, the upper of which is formed with a perforation, and a closure 75 element for closing the opening between said projecting members having a stem passing slidably and revolvably through the perforation in the upper projecting member of the bracket, the upper end of said stem 80 being bent over to provide a permanent connection between the bracket and closure element and the lower end of said element being formed with a projection adapted to be seated upon the lower projection of said 85 bracket when said element is in its closing position.

6. A device for supporting the operating rod of a coupler pin release rigging comprising a bracket adapted to be attached to 90 a car and provided with a lower channel-shaped projection and a projection above the same, and a closure element to close the opening between said projections which is slidably engaged with the upper projection 95 and has a channel-shaped part providing a bearing for the operating rod which fits into the channel-shaped projection of the bracket.

7. A device for supporting the operating rod of a coupler pin release rigging comprising a bracket adapted to be attached to 100 a car and provided with a lower channel-shaped projection and a projection above the same formed with a perforation, and a closure element to close the opening between 105 said projections which has a stem passing slidably and revolvably through the perforation in the upper projection and has a channel-shaped part providing a bearing for the operating rod which fits into the channel-shaped projection on the bracket.

8. A device for supporting the operating rod of a coupler pin release rigging comprising a bracket adapted to be attached to a car and provided with a lower channel-shaped projection and a projection above the same formed with a perforation, and a closure element to close the opening between said projections which has a stem passing 115 slidably and revolvably through the perforation in the upper projection and has a channel-shaped part providing a bearing for the operating rod which fits into the channel-shaped projection on the bracket, the upper end of said stem being off-set to permanently engage the closure element with the bracket.

9. A device for supporting the operating rod of a coupler pin release rigging comprising a bracket adapted to be attached 120

to a car and provided with a lower channel-shaped projection and a projection above the same formed with a perforation, a closure element to close the opening between 5 said projections which has a stem passing slidably and revolubly through the perforation in the upper projection and has a channel-shaped part providing a bearing for the operating rod which fits into the channel-

shaped projection on the bracket, the upper end of said stem being off-set to permanently engage the closure element with the bracket, and an outward projection at one of the vertical edges of the bracket adapted to form a bearing for the handle 15 end of the operating rod.

GARTH GRIFFITH GILPIN.
